UNITED STATES PATENT OFFICE.

JAMES CRAWFORD, OF BOSTON, MASSACHUSETTS.

ADJUSTABLE SUPPORT FOR TUBS OR SINKS.

SPECIFICATION forming part of Letters Patent No. 737,082, dated August 25, 1903.

Application filed December 2, 1902. Serial No. 133,573. (No model.)

To all whom it may concern:

Be it known that I, JAMES CRAWFORD, a citizen of the United States, and a resident of Boston, in the county of Suffolk and State of Massachusetts, have invented certain new and useful Improvements in Adjustable Supports for Washtubs or Sinks, of which the following is a specification.

This invention relates to improvements in adjustable supports for supporting what is usually termed "set" washtubs or sinks, and although particularly designed for such purpose it may be used as an adjustable support for other objects, if so desired.

The invention is carried out as follows, reference being had to the accompanying drawings, wherein—

Figure 1 is a front elevation of a washtub and sink supported on my improved adjustable brackets, parts of said figure being shown in section. Fig. 2 is a vertical section on the line 2 2 in Fig. 1, showing the base of the adjustable post in section. Fig. 3 is a detail top plan view of one of the improved adjustable brackets. Fig. 4 is an enlarged cross-section on the line 4 4 shown in Fig. 2.

Similar letters refer to similar parts wherever they occur on the different parts of the drawings.

A represents an ordinary soapstone washtub, and B represents a sink of the same material, such washtub and sink being shown as arranged side by side, as is common where set tubs are used. In devices of this kind the washtub is usually made somewhat deeper than the sink, as shown in Figs. 1 and 2. The said washtub and sink are supported at a proper distance above the floor by means of my improved adjustable supports, each one of which is constructed as follows: It consists of a metal base or foot C, resting on or suitably secured to the floor D of the room. The hub of said metal base is interiorly screw-threaded and adapted to receive the screw-threaded lower end of the metal post or standard E, preferably made tubular, as shown in Figs. 1 and 2.

F represents an adjustable bracket, preferably made of cast metal and provided at its lower portion with a tubular socket F', which receives the upper end of the post E, as shown in Figs. 1 and 2. It will thus be seen that

the bracket F may be vertically adjusted simply by turning the screw-threaded post E around its axis to the right or left, as may be desired.

I have shown the lower end of the post E screw-threaded and adjustable in the interiorly-screw-threaded base or foot C; but I wish to state that I do not desire to confine myself to this exact construction, as, if so desired, the upper end of said post E may be screw-threaded and adjusted in a screw-threaded socket on the bracket F without departing from the essence of my invention.

Each bracket F is provided at its upper horizontal portion with an adjustable plate G, as shown. Such plate G is adjustably secured to the bracket F, preferably by means of a headed fastening-bolt H, going through a slotted perforation f in the bracket F and a perforation in the plate G, or vice versa, and by this means the bracket F may be adjusted relative to the plate G according to the width of the tub or sink that is to be supported on said bracket. In practice I prefer to make the plate G angular in section, as shown in Figs. 1 and 4, and fitted into a corresponding recess in the upper portion of the bracket F, as shown. The plate G may be secured to the wall I by means of any desired fastening devices as may be most practical and convenient.

When the sink is arranged at the side of the washtub and close up to it, as shown in Fig. 1, I prefer to provide the bracket that supports the washtub at the end of and adjoining the sink with a pair of upwardly-projecting rods or tubes K K, suitably secured to said bracket. Upon the upper ends of said vertical posts K K rests a metal bar or plate L, having sockets l l for receiving the upper ends of said posts K K, as shown in Figs. 1 and 2. Said bar or plate L serves as a rest for the sink B at the end nearest to the washtub, as shown in Fig. 1. The forward end of the plate L is provided with a lip l', which serves as an abutment or stop against the lower front portion of the sink B, as shown.

The device is very simple in construction, and by means of it the height of tubs, &c., may be regulated as may be desired.

What I wish to claim is—

1. The herein-described adjustable support for washtubs and sinks, consisting of a base-plate, a screw-threaded vertically-adjustable post, a bracket connected thereto, and a horizontally-adjustable plate, all combined and constructed substantially as and for the purpose set forth.
2. The herein-described support for wash-tubs and sinks, consisting of a base-plate, a screw-threaded vertically-adjustable post, a bracket combined with a horizontally-adjust-

able plate, and vertical projections or rods secured to said bracket and a plate or bar L, having sockets l, l, supported on said rods substantially as and for the purpose set forth. 15

In testimony whereof I have affixed my signature in presence of two witnesses.

JAMES CRAWFORD.
